CAP DISPLAY FORM

Frank K. Lipschutz, Anchorage, Ky., assignor to Louisville Cap Company, Louisville, Ky., a copartnership

Application September 3, 1957, Serial No. 47,561

Term of patent 14 years

(Cl. D80—8)

Fig. 1 is a top plan view of a cap display form, embodying my new design the bottom plan view being substantially like the top plan view; and

Fig. 2 is a cross-sectional view, taken on the line 2—2 of Fig. 1.

I claim:

The ornamental design for a cap display form, substantially as shown and described.
